UNITED STATES PATENT OFFICE.

ANDREW PETER ANDERSON, OF NARBERTH, PENNSYLVANIA.

TOY.

1,282,724.

Specification of Letters Patent.

Patented Oct. 29, 1918.

Application filed January 31, 1918. Serial No. 214,694.

To all whom it may concern:

Be it known that I, ANDREW P. ANDERSON, a citizen of United States, residing at 321 Meeting House Lane, Narberth, in the 5 county of Montgomery and State of Pennsylvania, have invented new and useful Improvements in Toys, of which the following is a specification.

The invention relates to games and toys, 10 and has for an object to provide a novel form of balancing toy.

Among other features, the invention comprehends a toy which is preferably of an egg configuration, in which is contained a ball 15 weight similar to a marble, it being ordinarily impossible to stand the egg-like body on end, and have it remain so, until the ball weight has been brought into a certain position within the body, whereby the relation of 20 the weight to the egg-like body will permit of standing the latter on end, thus solving the puzzle, or completing the manipulation of the toy to obtain the desired result.

In the further disclosure of the invention, 25 reference is to be had to the accompanying drawing, constituting a part of this specification, in which similar characters of reference denote corresponding parts in all the views, and in which—

30 Figure 1 is a vertical sectional view taken through the toy, showing the internal construction and the general configuration.

Fig. 2 is a plan view of one of the halves of the toy, showing the formation of the 95 end thereof on the inside.

Referring more particularly to the views, the numeral 10 indicates the toy in its entirety, and which preferably consists of an egg-shaped body formed by two halves 11 40 which are adapted to have their enlarged ends meet to form a complete egg-shaped body, the body thus being hollow. Inasmuch as each half is exactly alike, I will preferably describe one of them, and refer to the halves 45 and parts thereof by similar numerals. The inner or smaller end of the half 11 is formed with an enlarged upstanding portion 12 providing a ledge 13 around which is formed a segmental groove 14, the groove or channel, 50 as it may be better called, being formed to terminate at a point 15, so as to provide an entrance to the ledge 13, or more particularly to a cup-shaped basin 16 formed in the top of said ledge. To one side of the entrance 15 55 there is provided a baffle 17, which may be secured in the material of the body in any

suitable manner, as shown, and loosely disposed in the egg-shaped body, or in any one of the halves thereof, is a ball weight 18 similar in shape and construction to a heavy 60 marble. The outer smaller extremity of the half 11 instead of being rounded at the end, is formed with a flat surface 19, which, however, is quite small, being made of only sufficient area to permit of standing the toy on 65 end, when the body lies in the vertical plane or axis of the body.

Now it will be clear that when the two halves, constructed similarly as mentioned and shown, are securely connected by gluing, 70 or otherwise, with the ball weight therein, it will be impossible to stand the body on either end until the ball weight has been seated upon one of the ledges and in one of the cup-shaped basins 16, and in order to accomplish 75 this, it is necessary for the operator to manipulate the toy until he can cause the marble to roll around one of the grooves 14 and pass through the entrance 15, to become seated in the cup-shaped basin 16 on the 80 ledge 13, and when this has been accomplished, the operator by careful manipulation can stand the toy on end on one of the flat faces 14 thereof, and the same will maintain this upright position.

It will be noted that the baffle 17 is provided to prevent the toy from being too easily operated to secure the desired result, and that clever manipulation of the toy is necessary in order that the ball weight can 90 be brought in the plane of the vertical axis of the body, whereby the toy can be stood on end, as described heretofore.

I claim:

1. A toy comprising an egg-shaped body, 95 plain faces formed on the outer surfaces of the extremities of the body, ledges providing seats, formed on the inner surfaces of the extremities of the body with annular grooves around the ledges, and formed to provide 100 entrances toward the basins of the ledges by cutting away portions of the ledges, and a ball weight loosely disposed in the body to be seated on one of the ledges.

2. A toy comprising an egg-shaped body, 105 plain faces formed on the outer surfaces of the extremities of the body, ledges providing seats, formed on the inner surfaces of the extremities of the body with annular grooves around the ledges, and formed to provide 110 entrances toward the basins of the ledges by cutting away portions of the ledges, a ball

weight loosely disposed in the body to be seated on one of the ledges, and baffles secured in said body to project into the grooves thereof adjacent the entrances from the 5 grooves to the basins of the ledges.

3. As a new article of manufacture, a toy comprising an egg-shaped body having flat faces on the outer surfaces at each end and

an enlarged portion on the inner surfaces of each end, said enlarged portions forming 10 ledges cupped to provide seats with grooves around said ledges, a ball weight loosely disposed in the body, and baffles secured within the body to project into said grooves.

In testimony whereof I affix my signature. 15
ANDREW PETER ANDERSON.
